LAWN SPRINKLER

Russell B. Nelson, Peoria, Ill., assignor to L. R. Nelson
Mfg. Co., Inc., Peoria, Ill., a corporation of Illinois

Filed Oct. 8, 1965, Ser. No. 87,370

Term of patent 14 years

(Cl. D91—1)

The essential features of my design reside in those features shown in full lines.

I claim:

The ornamental design for a lawn sprinkler, as shown and described.
